UNITED STATES PATENT OFFICE.

AXEL F. CARLSON, OF CAMBRIDGE, MASSACHUSETTS, ASSIGNOR TO THE REECE BUTTON HOLE MACHINE COMPANY, OF BOSTON, MASSACHUSETTS, A CORPORATION OF MAINE.

THREAD TRIMMER FOR BUTTONHOLE-SEWING MACHINES.

Application filed June 1, 1926, Serial No. 112,810. Renewed June 8, 1928.

This invention relates to sewing machines and particularly to means for trimming the thread at the end of the sewing operation. The invention is herein illustrated as embodied in a sewing machine of the type shown in my co-pending application Serial No. 79,523, filed January 6th, 1926.

In the device herein illustrated the tread trimmers are actuated at the end of each sewing operation by power mechanism which is normally idle but which is set in operation by the action of the stopping mechanism in bringing the sewing instrumentalities to rest. The trimming mechanism is of that known type which is constructed to trim the thread twice for each sewing operation, once at the completion of the sewing operation in order to cut the thread leading to the source of supply and again at the beginning of the next sewing operation.

Another feature of my invention relates to a novel trimmer adapted for these two trimming operations, which trimmer is formed with two oppositely-disposed cutting edges, one of which is active in trimming the thread at the end of the seam and the other of which is active in trimming the thread at the beginning of the seam.

The device also includes a novel pull-off mechanism for pulling off both the upper end the under thread at the end of the sewing operation and for holding each thread end during the time that the machine is at rest and until the next sewing operation is begun.

The invention further includes various novel features and constructions, all as will be more fully hereinafter set forth.

In order to give an understanding of the invention I have illustrated in the drawings a selected embodiment thereof which will now be described after which the novel features will be pointed out in the appended claims.

Fig. 1 is a side view of a sewing machine having the improvements applied thereto;

Fig. 2 is a plan view of the work-supporting arm and work clamps thereon together with the means for trimming the upper thread and holding the trimmed end;

Fig. 3 is a side view of Fig. 2;

Fig. 4 is a sectional view on substantially the line 4—4, Fig. 1, illustrating the power-actuating mechanism for operating the thread cutter;

Fig. 5 is a section on substantially the line 55 5—5, Fig. 4;

Fig. 6 is a fragmentary view illustrating the devices for controlling the driving clutch;

Figs. 7 and 8 are fragmentary views showing part of the power-actuated mechanism for operating the upper thread holder;

Figs. 9 and 10 are fragmentary views showing the power-actuated means for operating the upper thread cutter;

Figs. 11 and 12 are fragmentary views illustrating the operation of the upper thread holder and cutter;

Fig. 13 is a fragmentary view illustrating the mechanism for actuating the under thread trimmer and holder;

Fig. 14 is an enlarged fragmentary perspective view of the under thread pull-off device;

Fig. 15 is a view illustrating the under 75 thread cutter;

Fig. 16 is a view illustrating the under thread pull-off.

Fig. 17 is a section on the line 17—17, Fig. 3.

As stated above the present invention is shown as embodied in a sewing machine which is similar to that illustrated in my co-pending application Serial No. 79,523, filed January 6th, 1926, said machine being a two-thread buttonhole sewing machine. The sewing machine has the frame 1 from which extends the usual overhanging arm 2 carrying the upper thread-manipulating mechanism and from which also extends a lower horizontal work-supporting arm 3 on which the work *m* is supported. The upper thread-manipulating mechanism comprises the usual needle 4 which is carried by a vertically-reciprocating needle bar 5, and the under thread-manipulating mechanism, which is not shown herein, may be in the form of the usual oscillatory hook which takes loops of needle thread and casts them about a shuttle in a well-known way.

The operating mechanism is driven from a driving shaft 6 which in turn is actuated from a constantly-rotating driving pulley 7, the latter being driven by the driving belt 8. This driving pulley 7 is connected to and disconnected from the driving shaft 6 through the medium of a suitable clutch, (not shown), situated in a recess in the pulley 7, said clutch

being controlled by a cone-shaped clutch actuator 9 which is slidably mounted on the shaft 6, movement of the clutch actuator toward the left Figs. 4 and 6 throwing the clutch 5 into engagement and movement to the right into the position shown in Figs. 4 and 6 releasing the clutch.

The clutch actuator 9 is controlled by a clutch-controlling rod 10 which is slidably 10 mounted in the frame, said rod having fast thereon a forked arm 11, the fork of which engages in a groove 12 in the clutch-controlling member 9 so that movement of the rod 10 in the direction of its length will throw the 15 clutch into engagement or release the clutch. The clutch-actuating rod 10 is given its clutch-engaging movement by means of an elbow lever 13 pivoted to the frame at 14, the vertical arm 15 of said elbow lever engaging 20 the end of the rod 10. When the horizontal arm 13 is pulled downwardly the clutch-controlling rod 10 will be shifted to the left Figs. 4 and 6 thereby throwing the clutch into engagement and setting the machine in operation. 25

A suitable latch device is provided for automatically engaging the rod 10 when the clutch has been thrown into engagement, which latch device locks said rod in its operative 30 position and maintains the clutch in engagement. This latch is automatically released at the end of the buttonhole and when so released the rod 10 will be retracted into its inoperative position by means of a suitable spring 16. The latch for locking the 35 rod 10 in its operative position is indicated at 17 and it is adapted to engage automatically in a notch 118 formed in the rod 10 when the latter has been thrown into its operative position. The latch is released automatically by suitable mechanism, all as shown in my above-mentioned application.

The elbow lever 13 may be operated in any suitable way. It is herein shown as having 40 a link 18 pivoted to the horizontal arm, which link is adapted to be actuated by a treadle or other starting mechanism. The link is shown as extending through a head 19 fast on the end of a connection 20 that leads to a treadle 45 or other starting device, said link having a collar 21 thereon so that when the connection 20 is moved downwardly and the head 19 is brought against the collar 21 the elbow lever 13 will be actuated to throw the clutch. Said 50 elbow lever has a spring 22 connected thereto which tends to return it to its initial position shown in Fig. 4.

Associated with the starting mechanism above described is a stop mechanism by which 55 the machine is brought to rest at the end of the stitching operation. This stop mechanism is similar to that shown in my above-mentioned application Serial No. 79,523, and it comprises a stop motion block 88 which is rigidly mounted on the clutch-controlling rod 10 and

which yieldingly carries a stop dog 89 that co-operates with a stop cam 90 in bringing the machine to rest. This stop cam 90 is fast on the shaft 6. When the clutch-controlling rod 10 is shifted to the left Figs. 4 and 6 to 70 throw the clutch into engagement the stop motion block 88 and stop dog 89 are carried to one side of the path of movement of the stop cam 90.

When the latch 17 is released at the end of the stitching operation and the clutch-controlling rod 10 is shifted to the right into the position shown in Figs. 4 and 6 thereby releasing the driving clutch the stop dog 89 will be carried into the path of movement of the 80 stop cam 90 and during the rotation of the shaft said stop cam will engage the stop dog thus bringing the driving shaft 6 to rest.

The work *w* is held by a suitable work holder comprising under clamps 23 and upper 85 clamps 24. Both clamps are mounted on a work-supporting plate 25 which in turn is supported on the arm 3 so that it can move longitudinally of the arm and also transversely thereof. The movement longitudinally of 90 the arm is that which gives the work its feeding movement during the stitching along the side of the buttonhole and the movement transversely of the arm is that which gives the work a jogging movement for forming 95 the barring stitches at the end of the buttonhole all as usual in buttonhole sewing machines of this type. The means for giving the work holder its movement may be all as shown in my above-mentioned co-pending 100 application Serial No. 79,523, and as it forms no part of my present invention I have not deemed it necessary to illustrate it herein.

The upper work clamps 24 are carried by arms 26 which extend from the upper end of 105 a rocking member 27 that is pivoted on a shaft 28 carried by the clamp plate 25. These upper work clamps are yieldingly held against the work by means of springs 29 and at the end of each buttonhole they are raised 110 and held raised by means of a latch 30 which engages a projection on an elbow lever 31 pivoted at 32, the horizontal arm 33 of said elbow lever engaging the under side of the arms 26 thus holding them raised. 115

When the machine is started the latch is automatically released thus allowing the clamps to close and this is accomplished by a lever 34 pivoted to the bed at 35 and having a roll 36 adapted to engage a cam face 37 on the 120 under side of the latch. The lever 34 is connected by a link 38 with an elbow lever 39 which is pivoted to the frame and which has a link 40 connected thereto which extends through the head 19, said link 40 having a collar 41 thereon. The collar 41 is slightly 125 above the collar 21 and hence when the connection 20 is moved downwardly the initial downward movement will act through the connections 40, 39, 38 and 34 to raise the latch 130

30 and release the work clamps and continued downward movement will then throw the clutch into engagement and start the mechanism. The spring 42 acting on the lever 34 tends to return it to its normal position.

The work clamp and means for controlling it are or may be all as set forth in my co-pending application Serial No. 79,523 or my co-pending application Serial No. 112,507 filed May 29, 1926.

As stated above the present invention relates to a novel means for cutting the needle thread at the end of the sewing operation and holding the severed end until after the next stitching operation has been begun and then cutting the held end directly after the second stitching operation has been begun, and also novel means for trimming the under thread and holding the severed end, the thread trimmers and the thread holders being actuated by power mechanism which is normally inactive during the stitching on the buttonhole but which is thrown into operation by the stopping mechanism when the stitching on the buttonhole has been completed.

20 The upper thread trimmer is a blade 43 having the two oppositely disposed cutting edges 44, 45. This cutting blade operates in a transverse slot formed in one of the work clamps and is carried by a shank 46 which in turn is secured to the end of an arm 47 that is pivoted at 48 to one of the upper work-clamping arms 26. The cutter-carrying arm 47 is provided with a lateral extension 49 which is 30 acted upon by a spring 50 that normally tends to hold the cutter relative to the work clamps in the position shown in Figs. 11 and 12, in which position it is at one side of the line of sewing. The trimming of the thread 35 at the end of the seam is accomplished by a transverse movement of the blade into the position shown in Fig. 2 resulting from a swinging movement of the arm 47, as will 40 presently be described.

45 Associated with the upper thread cutter is a thread holder which seizes the needle thread between the needle and the work and holds or grips said thread while it is being cut and also maintains a hold on the thread until the next sewing operation has begun as usual in devices of this type. This thread holder is indicated at 51 and it is in the form of a hook carried by a swinging arm 52 also pivoted to the clamp-carrying arm 26 at 48. The arm 52 is acted on by a spring 53 which tends normally to move said thread holder from the position shown in Fig. 2 to that shown in Fig. 12.

66 This thread holder lies in contact with the upper surface of one of the work clamps and is adapted to grip the needle thread between itself and said work clamp.

During the stitching on the buttonhole the upper thread holder and cutter occupy the position shown in full lines Fig. 12. When the

stitch-forming mechanism has come to rest the thread holder is moved from the full line position shown in Fig. 12 back to the full line position Fig. 11 during which movement the thread holder engages the needle thread t , 70 pulls off a length thereof and clamps it against the upper face of one of the work clamps. After this has been done the cutter is moved into the position shown in Fig. 2 across the line of stitching and the edge 44 of the cutter will act to cut the needle thread t 75 between the thread holder and the work, the severed end of the thread leading to the needle being retained by the thread holder.

The thread holder 51 and thread cutter 43 are normally held by their springs 53 and 50 in the position shown in Fig. 12 and the operative movement of these parts into the position shown in Fig. 2, which is the movement by which the upper thread is gripped and cut, is derived from power-actuated mechanism which is normally idle during the sewing of the buttonhole, but which is rendered operative by the action of the stop motion in bringing the machine to rest. Such power-actuated mechanism comprises a cam 54 mounted on a stud 55 carried by the frame. This cam is normally idle during the stitching on the buttonhole but at the end of the stitching it is connected to a constantly-rotating member 56 through the medium of a one-revolution clutch so that the cam will make one revolution and then come to rest. During this one revolution the cam actuates a mechanism which moves the thread holder 51 and the thread cutter 43 positively into the position shown in Fig. 2, in which position they are latched as will be presently described.

The continually rotating member 56 is in the form of a gear member loosely mounted on the stud 55 and meshing with a gear 57 rigid with the driving pulley 7 so that the gear 56 will be rotating whenever the pulley 7 is rotating. 110

The clutch by which the cam is clutched to the gear 56 is similar to that shown in my co-pending application Serial No. 79,523 and also similar to that shown in the application of John Kiewicz, Serial No. 75,518, filed December 15th, 1925. This clutch comprises a clutch pin 58 carried by the cam 54 and acted on by a spring 59 which tends normally to throw the clutch pin into clutching engagement with the constantly-rotating member 56. Said clutch pin is normally held disengaged by means of a clutch dog 60. This clutch dog is in the form of an arm carried by a rock shaft 61 and when the shaft is turned anti-clockwise Fig. 1 the clutch dog will be raised out of engagement with the head of the clutch pin 58 and the latter will clutch the cam to the constantly-rotating member, said clutch pin being retracted again by the clutch dog when the cam has

made one revolution as usual in one-revolution clutches.

As stated above this clutch is actuated by the stop motion. The shaft 61 has fast thereon an arm 62 carrying an adjusting screw 63 which is adapted to be engaged by an arm 64 fast to the stop motion block 88. When the stop motion operates to bring the shaft 6 to rest as above described the engagement of the 10 cam 90 with the stop dog 89 will give the stop motion block 88 a slight clockwise movement (see Fig. 5) thus carrying the arm 64 into the dotted line position, in which position it will engage the stop screw 63 and give the shaft 15 61 the requisite turning movement to release the dog from the clutch pin, thus allowing the clutch to become operative to clutch the cam 54 to the constantly-rotating member 56. The movement of the arm 64 into the dotted 20 line position is momentary only and, therefore, as soon as the clutch pin has been released the clutch dog will return to its normal position shown in Fig. 1 ready to effect a disengagement of the clutch pin upon the completion 25 of the rotation.

The cam 54 operates a lever 65 fast on a rock shaft 66 and said rock shaft has fast thereon another arm 67 which is connected by a link 68 to a slide 69 that is slidably mounted 30 on the bed of the machine. The cam 54 gives the slide 69 a positive movement to the left Fig. 3 and such movement gives rocking movement to a rocking actuating member 70 which is pivoted to the bed at 71. This member 70 has a stud 72 extending therefrom on which is mounted a roll 73 and the slide 69 is provided with an inclined or cam face 74 that is adapted to engage the roll 73 when the slide is moved to the left Fig. 3. The engagement 35 of the cam face 74 with the roll during such movement of the slide will rock the member 70 toward the left Fig. 3 about its pivot 71, and such rocking movement will first operate the thread holder 51 to cause it 40 to grip the needle thread, as shown in Fig. 17, and will then cause the cutter to move into the position shown in Fig. 2 and dotted line position Fig. 17, thereby cutting the thread between the thread holder and the work.

The thread holder arm 52 is provided with a lateral extension 75 which is connected by a link 76 to a rocking member 77 pivoted at 78 to the member 27 that carries the upper work clamps.

The power-actuated member 70 carries a roll 79 which is adapted to engage the end face 80 of the rocking member 77 as shown in Fig. 7. The engagement of the roll 79 with the face 80 is at a point below the pivot 78 and hence as the member 70 swings toward the left Fig. 7 from the full to the dotted line position the engagement of the roll 79 with the face 80 will swing the member 77 into the position shown in Fig. 8 thereby drawing backwardly on the connection 76 and positive-

ly swinging the thread holder into the position shown in Fig. 2 against the action of the spring 53. This movement of the member 77 and thread holder occurs during the initial forward swinging movement of the member 70 due to the action of the slide 69. The member 77 is so constructed that after the swinging member 70 has reached the dotted line position Fig. 7 and has thus actuated the thread holder the roll 79 will pass onto the surface 179 which is at that time concentric with the pivotal axis 71 so that during further movement of the member 70 the roll simply moves forwardly on the surface 179 and thus holds the member 77 in the position shown in Fig. 8 while the thread cutter is given its thread-cutting movement.

The lateral extension 49 of the thread-cutter carrying arm 47 is connected by a link 83 to a swinging member 84 also pivoted on the pin 78 co-axially with the member 77. The stud 72 carried by the power-actuated member 70 has secured thereon a pusher or thrust member 85 which is adapted to engage the swinging member 84 at a point below its pivotal point 78, as shown in Fig. 9, and hence the swinging movement of the power-actuated member 70 will operate to swing the member 84 into the position shown in Fig. 10 and through the connection 83 give the cutter its thread-cutting movement, that is, movement from the full to dotted line position Fig. 17 or from a position shown in Fig. 11 to that shown in Fig. 2.

The construction is such that as the member 70 swings forwardly the roll 79 will act on the member 77 before the pusher 85 acts on the member 84. Hence during the initial swinging movement of the member 70 from the full to the dotted line position Fig. 7 the roll 79 will act on the member 77, as shown in Figs. 7 and 8, thereby actuating the thread holder and during the further swinging movement of the member 70 the pusher 85 will operate the swinging member 84 and thus give the thread cutter its thread-cutting movement. During this further swinging movement the roll 79 merely follows over the concentric face 179 and thus holds the member 77 in the position shown in Fig. 8.

When the member 70 has completed its forward movement and has swung the member 84 into the position shown in Fig. 10 both swinging members 77 and 84 will be automatically latched by a latch 81 which is pivotally mounted on the pivotal rod 28 and is adapted to engage teeth or shoulders 82 and 86 formed on the members 77 and 84 respectively. This latch is counterweighted as shown at 87 so that it automatically clicks over teeth 82 and 86 as the members 77 and 84 are operated.

With this construction, therefore, as the cam 54 makes its single rotation at the end of the sewing operation the thread holder will first be given a positive movement by said cam

from the position shown in Fig. 12 to that shown in Fig. 2 thereby gripping the needle thread and subsequently the cutter will be moved from the position shown in Fig. 12 to that shown in Fig. 2 thereby to cut the needle thread between the thread holder and the work and after the thread holder and cutter have been moved into these positions they are automatically retained in such positions by the latch 81.

When the stitching on the next buttonhole is started the end of the needle thread is still retained by the holder 51 and after the stitching has progressed to a certain point the thread cutter is released from the latch 81 and is allowed to swing into the position shown in Fig. 11 under the influence of its spring 50. During this movement the cutting edge 45 engages the end of the needle thread which is retained in the holder and trims it close to the work. Thereafter the thread holder 51 is released from the restraining influence of the latch 81 and is allowed to move into the position shown in Fig. 12 under the influence of its spring 53. The cutter and thread holder are then set in position ready for the operation of seizing and holding the thread at the end of the buttonhole and then cutting the thread. This releasing movement of the latch is accomplished through the medium of a cam projection 88 adjustably secured to the bed and with which the tail or end 87 of the latch engages during the feeding movement of the work. As the tail 87 rides up the inclined cam face 88 it will turn the latch as will be readily understood thus withdrawing it from the shoulders 86, 82.

In order that the cutter may be first released to cut the thread while it is still held by the holder the point of the tooth 86 is situated slightly above the point of the tooth 82 so that as the latch is swung downwardly by the weighted tail 87 riding over the projection 88 said latch will be withdrawn from the shoulder or tooth 86 thus releasing the thread cutter before said latch is withdrawn from the shoulder or tooth 82. This will give a proper sequence of operations in the release of the thread cutter and thread holder.

The machine herein shown is also provided with means for pulling off a length of under thread at the end of each sewing operation and then cutting the under thread close to and beneath the work. This under thread pull-off and cutter is also actuated from the rock shaft 66. The under thread pull-off is in the form of a resilient arm 91 (see Fig. 16) which is carried by a rocking member 92 pivoted at 93 to the under side of the bed frame. This rocking member has a fork 94 which embraces a stud 95 carried by a slide 96 which operates beneath the bed frame. The rear end of the slide is provided with an opening 97 in which is received the lower end 65 of a lever 98 that is pivoted to the frame at 99,

the upper end of said lever having a slot 100 therein in which is received a pin 101 carried by the lever arm 67. When, therefore, the rock shaft 66 is turned by the cam 54 thereby to operate the upper thread cutter, the corresponding movement of the arm 67 will operate through the lever 98 to force the slide 96 rearwardly. Such rearward movement will swing the member 92 and the pull-off arm 91 into the dotted line position Fig. 16 thus carrying the pull-off arm across the sewing opening 102 and engaging the under thread thereby pulling off a length of the latter.

This pull-off arm 91 is constructed so that it not only pulls off a length of under thread 80 but also grips and holds the under thread. For this purpose the wire forming the pull-off arm 91 is bent into a coil 103. In forming the coil the wire is given a backward turn, as shown at 104, Fig. 14, and then is bent into 85 the coil formation. This forms a tapering throat 105 which is so situated that when the pull-off arm swings into the dotted line position Fig. 16 the under thread *u* will be caught in the tapering throat 105 and will be gripped 90 slightly between the turns of the coil.

After the thread pull-off arm 91 has thus operated to pull off a length of thread and to grip the latter the under thread is cut by an under thread cutter 106. (see Fig. 15) which 95 is also actuated by the slide 96. This cutter is pivotally mounted at 107 on the top of the work-supporting arm 3 and beneath the work-holding plate 25, said plate being removed in Fig. 15 to better show the construction of the 100 cutter. This cutter 106 has a cutting edge 108 at its end which operates directly beneath the throat plate 109. Said cutter member 106 is connected at its rear end to a block 110 which is slidably mounted in a slot 111 in the 105 arm 3, said block having on its under side a pin 112 which is confined between two arms 113 and 114 carried by the end of the slide 96. The cutter member 106 also has a pin 115 depending therefrom and operating in an 110 inclined slot 116 formed in the bed.

With this construction the movement of the slide 110 toward the rear will produce a forward swinging movement of the under thread cutter due to the movement of the pin 115 in 115 the slot 116, such forward movement causing the cutting edge 108 to engage the under thread leading from the work through the throat plate 109 and thereby severing said thread close to the work.

The arms 113 and 114 are spaced apart so as to allow some lost motion and the purpose of this is to provide the proper time relation between the operation of the thread pull-off and the cutter, it being desirable that the pull-off should operate first to pull off a length of thread after which the cutter should operate to cut the thread. With the parts in the position shown in Figs. 15 and 16 it will be observed that during the first or initial move- 120 125 130

ment of the slide 96 the pull-off arm 91 will be swung toward the dotted line position Fig. 16 thereby pulling off a length of thread and after the lost motion between the arm 114 and 5 the pin 112 has been taken up then during further movement of the slide 96 the block 110 will be actuated thereby operating the under thread trimming knife.

The pin 95 is shown as acted on by a return 10 spring 117 which restores the parts to their normal position as the arm 65 passes down onto the low portion of the cam 54.

I have also provided herein a safety device 15 which has for its object to prevent the operation of the thread trimmers while the stitch-forming mechanism is in operation. In other words, this safety device positively holds the thread trimmers inoperative while the stitching is being performed and releases the thread 20 trimmers for operation only when the stitch-forming mechanism has been brought to rest.

It will be remembered that the trimmers are set in operation by the action of the stop motion in giving the arm 62 a momentary turning movement into the dotted line position 25 Fig. 5 thereby to release the clutch dog 60 and allow the clutch pin 58 to become operative to clutch the cam 54 to the constantly-operating member 56. The safety device is in the form 30 of a latch which is adapted to lock the arm 62 in the full line position Fig. 5. This latch is shown at 120 and is pivoted to the frame at 121. It is formed at its upper end with a nose 122 which is adapted to latch over the portion 35 123 of the arm 62, said portion having a lip 124 which engages the nose 122 and thus locks the arm 62 from movement. This locking latch 120 is shown in its inoperative position in Fig. 4 and it is acted on by a spring 125 40 which tends to swing it into its operative position in engagement with the lip 124.

Means are provided whereby the locking latch 120 will be moved into its inoperative position when the clutch-controlling rod is 45 released and is shifted into a position to render the stop motion operative. The arm 64 is provided with a lug 126 which engages a projection 127 on the locking latch when the stop motion block moves from the position it 50 occupies when the driving pulley 7 is clutched to the shaft 6 into the stopping position shown in Figs. 4 and 6 and such engagement of the ear 126 with the projection 127 swings the latch into the position shown in Fig. 4 and 55 thus unlocks the lever arm 62. When the rod 10 is shifted to the left Figs. 4 and 6 to start the machine by clutching the pulley 7 to the driving shaft 6 such movement carries the ear 126 away from the lug 127 and the spring 125 then 60 acts automatically to swing the locking latch into its operative position, in which position it locks the arm 62 from movement and thus prevents the possibility of the cam 54 being clutched to the constantly-driving member 56. When, however, the stop motion is actu-

ated to bring the serving mechanism to rest then the locking latch 120 will be released so as to permit the operation of the thread trimmers as above described.

The construction is such that when the 70 clutch-controlling rod 10 is shifted to clutch the driving pulley 7 to the shaft 6 the locking latch 120 will come into its operative position just before the stop dog 89 is moved out of engagement with the stop cam 90. Hence the 75 arm 62 will be locked just before the clutch is started in operation, the advantage of which is that there is no possibility that the cutters can be actuated accidentally except at the proper time in the sequence of operations. 80

While I have illustrated herein a selected embodiment of the invention I do not wish to be limited to the constructional features shown.

I claim:

1. In a buttonhole sewing machine, the combination with stitch-forming mechanism, of work-holding means, a thread holder, a thread cutter having two oppositely-disposed cutting edges, means to move the thread cutter in one direction to cut the thread at the end of the seam and in the other direction to cut the thread at the beginning of the seam. 90

2. In a sewing machine adapted to sew a short seam and then come to rest, the combination with stitch-forming mechanism, of work-holding means, a thread holder, a thread cutter having two oppositely-disposed cutting edges, power-actuated mechanism to move the cutter in one direction, and a spring 95 to move it in the other direction, movement in one direction operating to cut the thread at the end of the seam and in the other direction at the beginning of the seam. 100

3. In a sewing machine adapted to sew a short seam and then come to rest, the combination with stitch-forming mechanism, of work-holding means, a thread holder, a thread cutter having two oppositely-disposed cutting edges, power-actuated mechanism to move the cutter in one direction at the end of the seam thereby to trim the thread between the holding means and the work, a spring to move said cutter in the opposite direction at the beginning of the seam thereby to trim the 110 held end of thread. 115

4. In a machine adapted to sew a short seam and then come to rest, the combination with a stitch-forming mechanism, of work-holding means, a thread holder, a thread cutter having two oppositely-disposed cutting edges, power-actuated mechanism to operate the thread holder and the cutter at the end of the seam to cause the thread holder to hold the thread and the thread cutter to cut the thread between the holding means and the work, springs acting on said holder and cutter and opposing the power-actuated movement thereof, a latch to hold said holder and cutter in the position given them by the 120 125 130

power-actuated means, and means operated by the feeding movement of the work-holding means to release the latch to permit the holder and cutter to return to their normal position after the sewing operation has started.

5. In a buttonhole sewing machine, the combination with stitch-forming mechanism, of work-holding means, a driving and stop motion device for driving the stitch-forming mechanism and bringing it to rest, a thread holder, a thread cutter, power-actuated mechanism controlled by the stop motion device when the stitch-forming mechanism is brought 10 to rest to cause the holder to hold the thread and the cutter to cut the thread between the holding means and the work, and spring mechanism operating to actuate the cutter to cut the held thread at the beginning of the 15 seam.

6. In a sewing machine adapted to sew a short seam and then come to rest, the combination with stitch-forming mechanism, of work-holding means, a stop motion device for 20 operating the stitch-forming mechanism and bringing it to rest at the end of the seam, power-actuated means controlled by the stop motion device to pull off a length of needle 25 thread, clamp the needle thread, cut the needle thread between the thread-clamping means and the work, pull off a length of under thread and cut the under thread, and spring means operating to cut the upper thread at the beginning of the seam.

30 7. In a sewing machine adapted to sew a short seam and then come to rest, the combination with stitch-forming mechanism, of work-holding means, a stop motion device for 35 operating the stitch-forming mechanism and bringing it to rest at the end of the seam, power-actuated means controlled by the stop motion device to pull off a length of needle 40 thread, clamp the needle thread, cut the needle thread between the thread-clamping means and the work, pull off a length of under 45 thread and cut the under thread, spring means operating to cut the upper thread at the beginning of the seam, and means to lock the power-actuated mechanism from 50 operation while the stitch-forming mechanism is in operation.

55 8. In a buttonhole sewing machine, the combination with stitch-forming mechanism, of work-holding means, means to give the work-holding means a feeding movement, a driving and stopping mechanism for operating the stitch-forming mechanism and bringing it to rest at the end of the seam, a thread cutter having two cutting edges, 60 means operating independently of the stitch-forming mechanism but set in operation by the stop motion to move the thread cutter and cause one cutting edge thereof to trim the thread at the end of the buttonhole, and

means controlled by the feeding movement of 65 the work-holding means to give the thread cutter a movement to cause the other cutting edge to trim the thread at the beginning of the seam.

9. In a buttonhole sewing machine, the 70 combination with stitch-forming mechanism, of work-holding means, means to give the work-holding means a feeding movement, a driving and stopping mechanism for operating the stitch-forming mechanism and bringing it to rest at the end of the seam, a thread cutter having two cutting edges, a thread holder, means operating independently of the stitch-forming mechanism but set in operation by the stop motion to cause 75 the thread holder to grip the thread and the thread cutter to cut the thread with one cutting edge at the end of the buttonhole, and means controlled by the feeding movement of the work-holding means to cause the thread cutter to cut the thread with the other cutting edge after the seam has begun and to actuate the thread holder to release the trimmed end. 80

10. In a sewing machine, adapted to sew a short seam and then come to rest, the combination with stitch-forming mechanism, of work-holding means, a thread cutter having two oppositely-disposed cutting edges, and means to move the thread cutter in one direction to cause one cutting edge to cut the 90 thread at the end of the seam and in the other direction to cause the other cutting edge to cut the thread at the beginning of the seam. 95

11. In a sewing machine adapted to sew a short seam and then come to rest, the combination with stitch-forming mechanism, of work-holding means, a thread cutter having two oppositely-disposed cutting edges, power-actuated mechanism to move the cutter in one direction to cause one cutting edge to cut the 100 thread at the end of the seam, and a spring to move the cutter in the opposite direction to cause the other cutting edge to cut the thread at the beginning of the seam. 105

12. In a sewing machine adapted to sew a short seam and then come to rest, the combination with stitch-forming mechanism, of work-holding means, a thread cutter having two oppositely-disposed cutting edges, power-actuated mechanism to move the cutter 110 in one direction, and a spring to move it in the other direction, movement in one direction causing one cutting edge to cut the thread at the end of the seam and in the other direction causing the other edge to cut the thread at 115 the beginning of the seam. 120

13. In a sewing machine adapted to sew a short seam and then come to rest, the combination with stitch-forming mechanism, of work-holding means, a thread cutter having two oppositely-disposed cutting edges, power-actuated mechanism to move the cutter in one direction at the end of the seam, 125

to cause one cutting edge to trim the thread, a latch to hold said cutter in a position placed by the power-actuated mechanism, means to release the latch at the beginning of the seam, 5 and a spring to give said cutter a return movement thereby to cause the other cutting edge to trim the thread a second time.

14. In a buttonhole sewing machine, the combination with stitch-forming mechanism, 10 of work-holding means, a thread holder, a thread cutter having two oppositely-disposed cutting edges, means operative at the end of the seam to give the thread holder a movement to cause it to grip the thread and subsequently to operate the cutter to cause one edge thereof to cut the thread, and means operative after the next stitching operation has begun to move the cutter in the opposite direction to cause the other edge to cut the 15 held end of thread and then to move the thread holder to release said thread fragment.

15. In a buttonhole sewing machine, the combination with stitch-forming mechanism, of work-holding means having a feeding 20 movement, a thread holder, a thread cutter having two oppositely-disposed edges, means operative at the end of the seam to cause the thread holder to grip the thread and subsequently operate the cutter in one direction to 25 cause one cutting edge thereof to cut the thread, and means operated by the feeding movement of the work holder after the next stitching operation has begun to move the cutter in the opposite direction thereby to 30 cause the other cutting edge to trim the thread 35

and then to move the thread holder to release the thread fragment.

16. In a buttonhole sewing machine, the combination with stitch-forming mechanism, of work-holding means, a thread holder, a thread cutter having two oppositely-disposed cutting edges, power-actuated mechanism operative at the end of the seam to move the holder into a position to grip the thread and to move the cutter to cause one edge thereof 40 to trim the thread between the holder and the work, and means operative after the next seam has begun to move the cutter in the opposite direction to cause the other edge to cut the held thread and then to move the thread 45 holder to release the thread fragment.

17. In a buttonhole sewing machine, the combination with stitch-forming mechanism, of work-holding means having a feeding movement, a thread holder, a thread cutter 50 having two oppositely-disposed cutting edges, power-actuated mechanism operative at the end of the seam to move the holder into a position to grip the thread and to move the cutter to cause one edge thereof to trim the thread between the holder and the work, and means operated by the feeding movement of the work holder after the next stitching operation has begun to move the cutter in the opposite direction to cut the held end of 55 thread and then to move the thread holder to release the thread fragment.

In testimony whereof, I have signed my name to this specification.

AXEL F. CARLSON.
